UNITED STATES PATENT OFFICE.

ANDREW P. OLSON, OF CHICAGO, ILLINOIS

COMBINATION-TOOL.

1,257,383.

Specification of Letters Patent. Patented Feb. 26, 1918.

Application filed November 1, 1917. Serial No. 199,617.

To all whom it may concern:

Be it known that I, ANDREW P. OLSON, a citizen of the United States, residing at Chicago, in the county of Cook and State of

Illinois, have invented certain new and useful Improvements in Combination-Tools, of which the following is a specification, reference being had therein to the accompanying drawing.

10 My invention relates to a combined pencil protector, eraser holder, and cigar cutter, and it consists in the matters hereinafter described and then pointed out in the appended claims.

15 In the accompanying drawing—

Figure 1 is a side view of my device applied to a pencil;

Fig. 2 is a front view of the device applied to the sharpened end of a pencil;

20 Fig. 3 is a sectional view of the device on the line 3—3 of Fig. 1 and applied to the sharpened end of a pencil;

Fig. 4 is an end view of the device in position for use as a cigar cutter; and

25 Fig. 5 is an end view of the device.

The combined pencil protector, eraser holder, and cigar cutter represented in the drawing consists of a length or strip of thin metallic material, such as brass, bent back 30 upon itself in a cylindrical curve at its center to form a bow or body 10, which is not entirely closed at its lower end, and then projected from the open ends of the body in an opposite pair of arms 11 and 12 which

35 terminate at their free ends in inwardly bent wings 14 and 13 which are arranged in different planes and stand with their inner edges overlapping when the arms are spread to their outer position or relation. The arms

40 are curved in cross-section and are arranged so that they expand or extend outwardly from the body toward their free ends when they are in closed position as shown in Figs. 2 and 3. The wings are provided with openings or passages 15 which register when the arms are in their inner position and are large enough to receive the body of an associated lead pencil, and the inner wing 14 has a straight edge 16, the material of the wing

45 being sufficiently thin for its straight edge to form a cutting blade or being beveled to a knife edge to serve as a cutting blade. The body 10 contains and supports a length or

strip of rubber E whose ends project beyond the body to permit their ready use as an eraser and form an anchor to retain the device in the pocket of the garment of the user. The rubber strip is also transversely cut-away or recessed as at e to form a recess or pocket for the sharpened end of the pencil. 60 The material of the body may be resilient and set to stand in position to hold the free ends of the arms in their extended relation or spread apart as shown, or it may be non-resilient and the expansion or resiliency of 65 the strip E may be utilized to act as a spring to open the arms and maintain tension to hold them in this relation. When the arms are moved to their inner position or relation by pressure on their sides as shown in Figs. 70 1, 2 and 3 the pointed end of a pencil P may be inserted through the openings in the wings, and when the pressure is relaxed or released the spring action tends to force them apart so that the peripheries of the 75 wing-openings grip the body of the pencil as shown in Figs. 2 and 3 to hold the parts together. When the sharpened end of the pencil is thus gripped its projecting lead is protected by the arms. When the device 80 is used as a cigar cutter the arms are allowed to spring apart, the tip of the cigar C is inserted in the opening of the lower wing as shown in Fig. 4, and when the arms are moved to their inner position by pressure the 85 edge 16 will cut the tip off the end of the cigar.

I claim:

1. A device of the class described consisting of a thin strip of metal bent to form at one end a curved bow or body open at its lower portion and having an opposite pair of arms curved in cross-section and extending outwardly from the body toward their free ends, the arms being normally spread apart and being provided with an opposite pair of inwardly extending overlapping wings having passages therethrough adapted to register when the arms are pressed toward each other to their inner position. 90

2. A device of the class described consisting of a thin strip of resilient metal bent to form at one end a curved bow or body open at its lower portion and having an opposite pair of arms curved in cross-section and extending outwardly from the body toward 95 100 105

their free ends, the body being set to normally spread the arms, and the arms being provided with an opposite pair of inwardly extending overlapping wings having passages therethrough adapted to register when the arms are pressed toward each other to their inner position.

In testimony whereof I affix my signature in presence of two witnesses.

ANDREW P. OLSON.
